CONTAINER FOR DISPENSING EYE DROPS

James J. Mahoney and Charles L. Weckesser, Chenango County, N.Y., assignors to The Norwich Pharmacal Company, a corporation of New York

Filed June 5, 1967, Ser. No. 7,350

Term of patent 14 years

(Cl. D83—1)

The side and end not shown are the same as the respective side and end shown.

We claim:

The ornamental design for a container for dispensing eye drops, as shown and described.
